Primary Examiner — Marianne Pandozzi(74) Attorney, Agent, or Firm — Burns & Levinson LLP; Orlando Lopez; Marlo Schepper Grolnic(57) CLAIM

The ornamental design for a football-shaped container and base, as shown and described.

DESCRIPTION

FIG. 1 is a perspective view of a football-shaped container and base;

FIG. 2 is a front view of the football-shaped container and base;

FIG. 3 is a side view of the football-shaped container and base;

FIG. 4 is a top view of the football-shaped container and base;

FIG. 5 is a bottom view of the football-shaped container and base;

FIG. 6 is an exploded, perspective view of the football-shaped container and base; and,

FIG. 7 is a bottom plan view of the football-shaped container and base with the base removed for ease of illustration.

1 Claim, 7 Drawing Sheets(56)
